COMBINED RADIO AND CARTRIDGE RECORDER AND PLAYER

Minol Araki, Tokyo, Japan, assignor to Lloyd's
Electronics, Inc., Compton, Calif.

Filed Apr. 1, 1974, Ser. No. 456,815

Term of patent 14 years

Int. Cl. D14—01, 32

U.S. Cl. D56—4 B

FIG. 1

FIG. 2

Des. 238,815
Page 2 of 3

FIG. 3

FIG. 4

FIG. 5

FIG. 6

FIG. 1 is a front elevational view of a combined radio and cartridge recorder and player showing my new design;

FIG. 2 is a rear elevational view;

FIG. 3 is a top plan view;

FIG. 4 is a bottom plan view;

FIG. 5 is a right side elevational view; and

FIG. 6 is a left side elevational view.

I claim:

The ornamental design for a combined radio and cartridge recorder and player, substantially as shown.
